UNITED STATES PATENT OFFICE.

CLIFTON KINSLEY BAUMANN, OF NEW YORK, N. Y.

FABRIC-BOLT BOARD.

1,216,924.

Specification of Letters Patent.

Patented Feb. 20, 1917.

Application filed March 26, 1915. Serial No. 17,135.

To all whom it may concern:

Be it known that I, CLIFTON K. BAUMANN, a citizen of the United States, and a resident of the city of New York, borough 5 of Manhattan, in the county and State of New York, have invented a new and Improved Fabric-Bolt Board, of which the following is a full, clear, and exact description.

10 Among the principal objects which the present invention has in view are: to provide for renewal of index cards; to facilitate the handling of devices of the character mentioned; to increase the durability of articles of the character mentioned; to provide storage capacity in the article mentioned; to provide for re-use of the device; and to provide for branding the article with the name or style of the proprietor.

20

Drawings.

Figure 1 is a perspective view of a fragment of a bolt of cloth rolled upon a board constructed and arranged in accordance with 25 the present invention;

Fig. 2 is a perspective view of a fragment of a bolt of cloth rolled upon a board constructed and arranged in accordance with a modified form of the invention;

30 Fig. 3 is a similar view showing a modified form of the invention as applied to the board illustrated in Fig. 1;

Fig. 4 is a top side view of a bolt of cloth employing a board such as shown in Fig. 1 35 of the drawings;

Fig. 5 is a longitudinal section of the board shown in Fig. 1, taken as on the line 5—5 in Fig. 4, the view being shown on an enlarged scale;

40 Fig. 6 is an end view on a reduced scale, of the board shown in Fig. 5;

Fig. 7 is a top side view of the modified form of board indicated in Fig. 2;

45 Fig. 8 is a longitudinal section on an enlarged scale, the section being taken as on the line 8—8 in Fig. 7;

Fig. 9 is a fragment of a longitudinal section similar to Fig. 5, showing the modified form of the invention disclosed in Fig. 3.

Description.

As seen in the drawings, two styles of board are employed. The boards such as shown in Figs. 1, 3, 5 and 9 of the drawings 55 are employed for rolling heavy fabrics, or fabrics apt to break when bent to a rela-

tively sharp curve, such as certain of the heavier silks. In Figs. 2, 7 and 8 of the drawings, a relatively thin board is shown, this style of board being peculiarly adapted 60 for wrapping thin and more pliable materials, such as chiffon, which are not so liable to crease or break by the quick turn resulting from rolling the fabric upon this style of board.

The boards 15 are hollow and are preferably constructed of light metal. The sides are supported by the heads 16, being rigidly secured thereto to form hollow cylinders or box-like forms. In the preferred 70 form shown in Figs. 1 and 5, the heads 16 are solid. In the modified form shown in Figs. 3 and 9, the heads 17 employed are provided with elongated openings 18, which, when exposed, form entrances to the interior of the board 15; both forms of head, however, support card-holders such as 19 and 20. The card-holders 19 and 20 differ only in that the back 21 of the card-holder 19 is solid, while the back 22 of the card-holder 20 has an opening therein to register with the opening 18 in the head 17 to which it is applied.

As shown in Figs. 1 and 3 of the drawings, one end of the card-holders 19 and 20 85 is open to permit the insertion of tag-cards 23 in the grooves formed by the overturned edges 24 of said card-holders. The grooves thus produced form runways for guiding and holding said tag-cards in service.

In some instances, and particularly when employing the card-holder 19, the back 21 thereof has imprinted or impressed thereon the name and address of the proprietor of the board, as is indicated by the words "John 95 Doe" in Fig. 1 of the drawings. When the card holders are thus stamped and attached to the board it will be seen that the boards may be used for purposes of shipment, said boards being returned by the proprietor to 100 the mill to be used by the mill for rolling the cloth, for delivering to the proprietor whose name is attached to the board. In this manner the boards may be individualized, and receive greater care and also 105 operate to reduce the factor of error in the filling of orders received by the mill.

When employing boards of construction such as shown in Fig. 1 or 3 of the drawings, the tag cards 23 may be renewed or replaced 110 after the same become soiled due to the changing of the pencil indexes on said cards,

or due to discoloration owing to the length of time during which the cards have been exposed. Oftentimes a bolt of cloth deteriorates or is prejudicially affected by the 5 fact that the tag-card connected therewith shows evidence of age or use. It is to avoid this objection and the consequent deterioration which makes it desirable to from time to time renew said cards.

10 The board 25 embodying the modified form of the invention has a card-holder 19 at each end thereof. The card-holders 19 are disposed on opposite sides of the board 25, and are held between the beaded edges 15 26 of said board. The tag cards 23 are placed in the holders 19 when applied to the boards 25, in the same manner as above described as when said holders are applied to the boards 15.

20 When the fabric is rolled on the boards 25, the card-holders 19 and cards 23 therein are normally concealed. The salesman adopts the expedient of lifting the relatively free fabric sufficiently to glance beneath to 25 there read the inscription of the card 23. If it becomes necessary or expedient to renew or replace the cards 23, this is done by drawing the board 25 carefully from the interior of the fabric until the holder 19 is sufficiently extended to remove the old card 23 and substitute a new one therefor. If desired, the backs 21 of the holders 19, when 30 applied to the board 25, have imprinted or impressed thereon the name or style of the 35 owner.

When using the boards embodying the modification shown in Figs. 3 and 9 wherein in the opening 18 is closed in service by the cards 23, the cards 23 are utilized as doors.

40 The interior of the boards 15 as thus constructed, may be employed as a receptacle for samples or for any accessory needed in the handling of the goods. When it is desired to remove a sample or other article

from the board 15 having the opening 18, 45 the card 23 is withdrawn from the holder 20. After the removal the card is replaced.

It will be observed that without reference to the end-to-end arrangement of the boards 15 or 25, the card-holders 19 and 20 are 50 held in view or in position to be readily viewed.

When employing boards constructed and arranged as above described and as shown in the accompanying drawings, said boards are 55 preserved and when denuded of the fabric rolled thereon, are forwarded or otherwise delivered to the manufacturer or mill to be re-supplied with fabric. New cards, such as 23, are then applied to the holders 19 60 and 20 and the re-supplied boards are forwarded to the owner of the boards or purveyor of the goods. It will be observed that if the card-holders are branded with the name of the owner in the manner set 65 forth, the liability to error in the filling of the order, is materially reduced.

In the modified form shown in Figs. 3 and 9, a sample-box 27 is employed, which box carries the holder 20. The box 27 is divided 70 lengthwise by a partition 28, as seen best in Fig. 3.

Claim.

A fabric bolt board comprising a flattened cylinder; a plurality of outwardly-opening 75 boxes rigidly connected with said cylinder; a card-holding frame surrounding the openings of said boxes and forming entrances therefor, said frame having overturned 80 edges; and a plurality of cards for closing said entrances.

In testimony whereof I have signed my name to this specification in the presence of two subscribing witnesses.

CLIFTON KINSLEY BAUMANN.
